UNITED STATES PATENT OFFICE.

WILLIAM WRIGHT, OF WILLINK, NEW YORK.

CHIMNEY-PROTECTOR.

SPECIFICATION forming part of Letters Patent No. 402,641, dated May 7, 1889.

Application filed June 25, 1886. Serial No. 206,191. (No model.)

To all whom it may concern:

Be it known that I, WILLIAM WRIGHT, of Willink, in the county of Erie and State of New York, have invented a new and useful 5 Improvement in Chimney-Protectors, which improvement is fully set forth in the following specification and accompanying drawings, in which—

Figure 1 is a side view of a section of a 10 chimney with my improved protector, having the side partly broken away mounted thereon; Fig. 2, a front view of one of the gable-sections detached; Fig. 3, a perspective view of one of the external parts of the gables, 15 showing the lugs formed integral therewith. Fig. 4 shows a modification in the shape of the roof.

My invention relates to improvements in chimney-protectors, and has for its object the 20 provision of a chimney cap or protector, which can be made and put on the market and adapted to be put in position upon finished chimneys and fastened thereon.

To this end my invention consists in a cast- 25 iron body and removable wall-pieces adapted to be secured to the body, so as to embrace the chimney and clasp it firmly, as will be hereinafter described, and then pointed out in the claims.

30 In the accompanying drawings, A represents this upper part of an ordinary chimney having thereon my improved protector. This consists of a top or roofing piece, B, preferably a casting forming a single piece having 35 four gables, C, two of which are in the same horizontal line and at right angles with the other two. These gables may be of any pitch desired. On the inner side of the gable I provide lugs D, preferably formed integral 40 with the roofing-piece and having openings therein. Within each of these gables I provide suitable vertical wall-pieces, E, also preferably cast, having openings F therein at suitable places, whereby the said wall-pieces 45 E may be attached to the lugs D by means of bolts.

At the upper part of the gable beneath the roofing-piece B, I provide a triangular piece, G, also formed integral with the said roofing- 50 piece, with an opening therein to act in the same capacity as the lugs D. The lower part

of this device may have a flange, H, securely attached to both the roof-piece B and vertical wall-piece E, so disposed as to fit down over the wall of the chimney A. 55

The pieces H may, as desired, be formed of sheet metal or tin, and need not necessarily be cast, though sometimes I find it convenient to cast them integral, either with the roofing-piece B or the vertical gable-pieces E. Each 60 of the gable-pieces E is provided with a central opening, I, of suitable size for the passage of the smoke from the chimney.

It will be observed that in practice the roofing-piece is rested on the top of the chimney 65 and the wall-pieces are then attached to the same, being bolted tightly thereto, so as to be drawn up closely against the chimney and clasp the same, thereby firmly securing the 70 protector in position.

The modification shown in Fig. 4 relates to curving the upper part of the roofing-piece instead of making it angled, while the lower part is so arranged or disposed as to flare outwardly. There is no change, however, in the 75 essential idea above presented.

Having described my invention, what I claim as new is—

1. A chimney-protector comprising the roofing-piece cast in a single piece, and the wall-pieces attachable thereto by means substantially as shown, whereby they are adjustable, 80 so as to fit against and firmly embrace the chimney and secure the protector in position, substantially as set forth. 85

2. The combination, with the roof-piece B, having the right-angled gables C formed integrally therewith in a single piece of cast-iron, of the wall-pieces E, provided with the openings I and removably secured in the 90 gables by means, substantially as shown, whereby said wall-pieces are adjustable, so as to fit against and firmly embrace the chimney, as and for the purposes set forth.

In testimony that I claim the foregoing I 95 have hereunto set my hand, this 29th day of April, 1886, in the presence of witnesses.

WILLIAM WRIGHT.
